PNEUMATIC VIBRATOR AND PRESS

William E. Gross, Joppa, Md.

Application February 15, 1938, Serial No. 190,599

2 Claims. (Cl. 259—72)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a pneumatic vibrator and press particularly adapted to pack activated carbon in an air purifying device.

During an attack by chemical warfare agents, certain essential industries must continue, such 10 as operation of water pumping stations, and electric power plants. In order that the air supplied to workers in these industries may be cleansed of the warfare agents, it has been proposed to draw the air through a device containing purifying 15 chemicals. One such device is an elongated tube containing granular activated charcoal. It is desirable that the charcoal in these tubes be packed uniformly and to a maximum density without crushing the charcoal.

20 One object of this invention is to provide a machine wherein the activated charcoal may be quickly packed to uniform density in an air purifying tube.

Another object of this invention is to provide a 25 machine wherein the activated charcoal is uniformly compacted without crushing in an air purifying tube, and the cover for such tube is simultaneously positioned on the tube.

These and other objects of the invention will 30 be apparent from the following description and claims.

Figure 1 is a front elevation of the machine with parts in section.

Figure 2 is a side elevation.

35 Figure 3 is an elevation of the air purifying tube, with the lower end in section.

Figure 4 is a section of the check valve in one air line.

The machine comprises a frame formed of two 40 side pieces 1 which may be channel irons, with a top channel 2 suitably secured to the side members, the whole machine being suitably mounted on a rigid base. The top 2 has supported therefrom an air cylinder 3 containing a double acting 45 piston. The lower end of the piston carries a top chuck 4 which supports the upper end of the air purifying tube and seats the top thereof in place.

The air purifying tube shown in Figure 3 comprises a sheet metal tube having a bottom 6 and a top 7. This tube is adapted to receive a definite quantity of activated charcoal granules which are heaped up about $\frac{1}{4}$ inch above the top rim. Tube 5 is then placed in the machine with the bottom 9 55 supported on bottom chuck 8. A cross support 9

is provided with a semi-circular recess 11 arranged to receive the upper portion of tube 5 and hold it in alignment with upper chuck 4.

The lower chuck 8 is mounted directly over a pneumatic hammer 12 which causes the chuck 8 5 and filled tube 5 to vibrate. Details of the pneumatic hammer are not shown as they form no part of the present invention. One form which has been used successfully has a 1.06 inch bore and an 8 inch stroke. Air pipe 13 supplies compressed air to the hammer under control of a valve 14 which is controlled by a foot lever 15.

Valve 14 is a four-way, two-position valve which controls the flow of air to air cylinder 3 and pneumatic vibrator 12. Pipe 16 is connected to a 15 source of compressed air and has a cut-off valve 17, an air filter, sediment bulb and bleeder valve 18, and a lubricator 19 connected therein. The combination air filter, sediment bulb and bleeder valve 18 has a removable fine mesh screen to 20 strain or filter the air and is fitted with a pet cock at the bottom for drawing off accumulated water. Lubricator 19 slowly feeds drops of light lubricating oil into the air supply to lubricate the vibrator and air cylinder. Pipe 16 is connected to control 25 valve 14.

Also connected to valve 14 is pipe 21 which allows air to flow to the vibrator 12 and to the upper end of air cylinder 3. Pipe 13 from vibrator 12 is joined to pipe 21 with an adjustable 30 cut-off valve 22 interposed in the line. By adjusting valve 22 the severity of the hammer blows to the vibrator may be varied to suit the requirements of different lots of chemical tubes and charcoals.

Pipe 23 having cut-off valve 24 therein is connected to control valve 14 by way of pipe 21 and leads to the upper portion of air cylinder 3. Pipe 25 is connected to control valve 14 and to the lower portion of cylinder 3. A check valve 26 is 40 interposed in line 25, as shown in Fig. 4. Valve 26 has a pivoted valve member 27 with an opening 28 therethrough. When air under pressure rises in pipe 25 from control valve 14, member 27 remains on its seat and the air passes through 45 opening 28, so that the piston in air cylinder 3 rises slowly without jar. When the piston descends due to pressure above it, the valve member 27 opens and allows rapid descent of the piston.

Operation of the machine is as follows. The 50 tube 5 is filled with charcoal or other material to be compacted without crushing, the charcoal usually being heaped over the open upper end. The lower end 6 of the tube is then placed on lower chuck 8, the upper portion being positioned 55

- in groove 11 of support 9. A top 7 (Figure 3) is then placed on upper chuck 4 and lever 15 of valve 14 is depressed. Compressed air then passes from inlet pipe 16 to pipe 21 and pipes 13 5 and 23 to the vibrator 12 and upper portion of air cylinder 3. Piston in cylinder 3 descends rapidly, since check valve 26 opens fully, and cover 7 is lightly seated on the upper end of tube 5.
- 10 Vibrator 12 taps chuck 8 which causes a uniform settling and compacting of the charcoal. The piston in air cylinder 3 allows a slight reciprocation of tube 5 at each impact of the vibrator, without however interposing sufficient resistance to cause deformation of the tube 5. This yielding upper chuck 4 gradually forces the top 7 in place in tube 5. It will be seen from Figure 3 that the top is centrally cupped so that the copper portion enters tube 5 about $\frac{1}{2}$ inch.
- 15 20 Pressure on pedal 15 is then released and a spring thereon reverses the valve 14, so that air is cut off from pipe 21 and enters pipe 25. Vibrator 12 stops, air cylinder 3 gradually and steadily raises chuck 4, and the filled tube is 25 removed and another tube inserted.
- Activated charcoal compacted into tubes by this invention is not crushed and is packed to an even density and during subsequent use and rough handling will not channel. The tubes may 30 be readily inserted and removed and the compacting is rapidly accomplished, usually in about 15 seconds.

It will be understood that the invention is not

limited to the details of construction herein shown by way of illustration, since changes and variations will readily occur to those skilled in the art without departing from the spirit of the invention nor exceeding the scope of the appended claims. 5

I claim:

1. A machine for compacting loose material in a container comprising an upper chuck and a lower chuck for vertically supporting a container, a vertically movable piston mounted in a cylinder, said piston carrying the upper chuck, a pneumatic hammer arranged to impart vertical blows to the lower chuck, compressed air supply pipes connected to said cylinder above and below 15 said piston and to said pneumatic hammer, a four-way two-position valve connected to a source of compressed air and to said pipes, said connections being so arranged that one position of said valve connects the source of compressed air to the cylinder above said piston and to the hammer, whereby the upper end of the container is resiliently pressed downward while the lower chuck is being tapped by the hammer, the other position of the valve admitting compressed air 20 below the piston to raise the upper chuck and to cut off air to said hammer.

2. The invention as defined in claim 1 wherein the pipe connected to said cylinder below the piston has a check valve therein, said check valve 25 allowing rapid descent of the piston and slow ascent thereof.

WILLIAM E. GROSS.
